EXPANSION BOLT

Filed June 14, 1928

UNITED STATES PATENT OFFICE

LOTHAR R. ZIFFERER, OF COLUMBIA, PENNSYLVANIA

EXPANSION BOLT

Application filed June 14, 1928. Serial No. 285,235.

This invention relates to an expansion bolt having a shield with two pivoted sections between which is an expander in the form of a wedge nut.

5 The present improvements are directed to means for holding a work engaging bolt against movement relative to the expander within the shield, so that even though the work should become loose the attaching bolt 10 therefore will not do likewise, but will remain dependably in the position to which it is originally adjusted.

An exemplification of my invention is set forth in the accompanying drawing in the 15 manner following:

Figure 1 is a view in elevation of the shield as it appears when first introduced into the hole prepared for its reception in a body of masonry, concrete, or the like;

20 Fig. 2 is a similar view showing the shield advanced longitudinally to final position within the hole, the shield being initially expanded during this movement;

Fig. 3 is a similar view of the shield sections as they appear when further expanded 25 upon application of the work engaging bolt to the expander;

Fig. 4 is a longitudinal section through the shield with the parts positioned about as 30 shown in Fig. 3;

Fig. 5 is an enlarged detail in section of the expander and associated parts;

Fig. 6 is a transverse section taken on line 6-6 of Fig. 4; and

35 Figs. 7 and 8 are vertical sections through the expander, taken in planes in right angular relation.

In a body A of concrete, masonry, or the like a hole B is provided for the reception 40 of the present expansion bolt which comprises a pair of shield sections C and C' substantially alike. One of these sections may be equipped with a pair of lugs 8 which overlaps the other section whereon are provided 45 laterally extending pins 9 extending through apertures in the lugs whereby to establish a pivotal connection between the two sections of the shield. This connection, it will be noted, is near the outer shield end so as to 50 permit the inner ends of the shield to swing

apart freely a limited distance in response to forces of expansion produced by advance of a wedge nut D. This free swinging movement is arrested when the outer ends of the shield sections come together, as shown in 55 Fig. 2. The outer surfaces of the two shield sections may be provided with ribs 10 and 11 disposed circumferentially and longitudinally so as to resist longitudinal and rotary movements of the expansion when the shield sections are engaged with the wall surfaces surrounding the hole B.

The interior of each shield section is provided with a concave inclined surface 12 against which the expander exerts an increasing pressure as it is advanced toward the outer end of the expansion. The expander, as best shown in Fig. 6, is in the general form of a truncated cone having an elliptical cross section whereby to provide tapering 70 sides 13 adapted to engage with the inclined surfaces 12 upon the interior of the shield sections. For the major portion of its length, the expander is split by the provision of slots 14 which, as shown, are arranged oppositely 75 in the plane of its shorter axis. Each of these slots proceeds from its inner larger end close to the outer smaller end, and may terminate in an enlargement 15 of such character as to facilitate bending of the two split nut 80 sections in response to a sufficient force which is developed for this purpose. The outer smaller end of the nut is continuous so as to have the form of a collar 16. The nut is threaded interiorly at 17 to cooperate with 85 the screw threads of a bolt E adapted to pass through the work F so as to present the bolt head 18 in engagement therewith. The threaded hole which is extended lengthwise of the nut is preferably tapered slightly toward its outer collared end whereby the inner threaded sections of the nut are normally spaced from the threads of the inner end of the bolt which extends therethrough. It will 90 be noted, by reference first to Fig. 5 and then to Fig. 4, that as the nut is drawn into the shield between the inclined surfaces 12 that the spaced sections are caused to bend inwardly from the enlarged ends 15 of the slots 95 14, causing the sections intermediate the ends 100

of the nut to bind upon the sides of the bolt, which binding progressively increases at this point as the inner spaced portions of the nut are contracted upon the inner threaded end 5 of the bolt, thus offering an increasing resistance to the passage therethrough of the threaded bolt.

The present expansion shield is adapted to be anchored in a hole having a depth slightly 10 in excess of its own length. The expander may initially project beyond the inner end of the shield, as shown in Fig. 1, thereby causing the outer shield end to protrude from the hole for a slight distance. By a blow from a 15 hammer or other implement the shield may be driven into the hole to the final longitudinal position which is indicated in Fig. 2. In so doing, the expander is forced further into the shield whereby to produce an initial expansion of its two sections. While in this 20 position, the shield will remain stationary during application of the bolt E which passes through the work and into the expander preliminary to further separation of the shield 25 sections. The bolt is adapted to enter freely into the continuous upper end of the expander where no appreciable distortion can take place. As the bolt is screwed further into the expander, it encounters an increasing friction 30 owing to the slight taper of the threaded split sections of the nut. By the application of a sufficient torsional force the bolt will be required to pass through the expander as far as necessary, thereby drawing the same 35 outwardly when the bolt head 18 engages with the work. The final position of the expander may be well toward the outer end of the shield sections, depending upon the degree of expansion which is required for producing a 40 secure anchorage.

The present expansion bolt is advantageous on account of the several features already referred to. It is also capable of expansion to an unusual degree. The pivoted outer end of 45 the expansion is unaffected to any considerable extent by the separation of the two shield sections, due to the spreading movement thereof being confined mostly to the inner end of the device. In case it becomes necessary to 50 withdraw the bolt for removal of the work, the split sections of the nut, which may be two or more, will continue to remain tightly wedged against the tapering interior surfaces of the shield so as to prevent collapse of its 55 sections, thereby preserving the parts in condition for further service when the bolt is reintroduced. Also, because of the friction obtaining between the bolt and the expander, the former will not tend to unscrew should the work become loose for any reason. This 60 is of particular advantage where the expansion is used to fasten a seat to the floor, it being a common fault that once the seat starts 65 to work loose the bolt will also tend to loosen

its hold on the expander until finally it disengages completely therefrom.

I claim:

An expansion bolt which is comprised of a pair of separable shield sections with inner tapering surfaces, a bolt arranged axially of the shield between the sections thereof, and an expander in the form of a wedge nut in co-operation with the bolt adapted to be advanced longitudinally of the shield against the tapering surfaces of its two sections, the nut comprising a plurality of spaced sections integrally joined at the outer end by a collar and having threads formed interiorly of the collar and extending for the length of the several sections of the expander, the axial opening through the expander increasing slightly in diameter from the collared end to the ends of the several sections, whereby upon axial movement of the expander into the inclined ends of the shield said threaded sections are contracted upon the bolt, progressively increasing resistance to movement of the bolt therebetween.

In testimony whereof I have hereunto set 90 my hand this 7th day of June, 1928.
